CLAIM

The ornamental design for an attachment points for snorkel on a vehicle, as shown and described.

DESCRIPTION

FIG. 1 is a front left perspective view of attachment points on snorkel for a vehicle, showing our new design;

FIG. 2 is a right rear perspective view thereof;

FIG. 3 is a left side elevation view thereof;

FIG. 4 is a right side elevation view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines illustrate portions of the attachment points for snorkel on a vehicle which form no part of the claimed design. The broken lines may also define a claim boundary. Neither the broken lines themselves nor the area within the broken lines form any part of the claimed design.
